UNITED STATES PATENT OFFICE.

RICHARD LEHMANN, OF BERLIN, GERMANY.

AERIAL PROJECTILE.

948,177.

Specification of Letters Patent. Patented Feb. 1, 1910.

Application filed January 2, 1909. Serial No. 470,397.

To all whom it may concern:

Be it known that I, RICHARD LEHMANN, a subject of the German Emperor, and residing at 140 Invalidenstrasse, Berlin, Germany, have invented certain new and useful Improvements in Aerial Projectiles, of which the following is a specification.

This invention relates to an improved aerial projectile having supporting and steering surfaces which enable the projectile to make a soaring flight whereby the flight of the projectile is increased and the force required for projecting the projectile is diminished.

15 The improved projectile has a tubular elongated body which serves as a gun barrel and as a guide in being discharged; it is adapted to be slipped over a rod or spindle for aiming.

20 The improved projectile is adapted for use as a toy. When constructed for use as a toy for children, the body of the projectile is made hollow for slipping over a blow pipe for the purpose of being projected by 25 a blast of air. In this form the improved projectile is preferably provided at the front end of its body with a weight for the purpose of imparting the desired acceleration to the projectile and of preventing the latter 30 from turning or tipping up or down.

Rotation of the projectile on its longitudinal axis may be prevented very simply by the provision of longitudinal side steering surfaces on the body.

35 One form of the improved projectile is illustrated in a diagrammatic perspective view in the accompanying drawing.

c is a blow pipe over which the tubular elongated body, d, of the projectile is adapted to be slipped for the purpose of projection. The body, d, is provided with lateral steering surfaces, a' and a''. Four surfaces, b', b'', b''' and b'''' are fixed on the rear part of the body for the purpose of imparting stability 45 to the projectile during flight. In the construction shown in the drawing, a weight in the form of a sharp pointed cone is provided on the forward end of the body, d.

50 When constructed for use as a toy, it may be projected by other means besides a blow pipe, such as by slipping the hollow body upon a centered arrow from which the projectile receives the impetus produced by an archer's bow or by a spring or a strong rubber cord or the like.

Having now described my invention what I claim as new and desire to secure by Letters Patent is:

1. An aerial projectile comprising an elongated hollow body, and a plurality of longitudinally disposed flanges mounted upon the exterior of said body, said flanges constituting supporting and steering planes.

2. An aerial projectile comprising an elongated hollow body, and a plurality of longitudinally extending relatively angularly disposed flanges mounted upon the exterior of said body, said flanges constituting supporting and steering planes.

3. An aerial projectile comprising an elongated hollow body, and a plurality of longitudinally disposed flanges mounted upon the exterior of said body, and extending substantially the entire length of said body, said flanges constituting supporting and steering planes.

4. An aerial projectile comprising an elongated hollow body, and a plurality of longitudinally disposed flanges mounted upon the exterior of said body and relatively angularly disposed and flanges of less length than the said first-named flanges disposed adjacent the rear end of said projectile and angularly disposed with relation to said first-named flanges, said flanges constituting supporting and steering planes.

5. An aerial projectile comprising a hollow cylindrical body equipped at one end with a tapered head and opened at its other end, a plurality of longitudinal ribs on said body extending substantially the entire length thereof, and flanges disposed on said body between the ribs thereof and between the ends thereof, said ribs and flanges constituting supporting and steering surfaces for said projectile.

6. An aerial projectile comprising a hollow cylindrical body equipped at one end with a tapered head and opened at its other end, a plurality of longitudinal ribs on said body extending substantially the entire length thereof, and flanges disposed on said body between the ribs thereof and between the ends thereof, said ribs and flanges constituting supporting and steering surfaces for said projectile, said ribs being angularly disposed relatively to each other and to said flanges.

7. The combination with a cylindrical fluid pressure member, of a hollow cylin-

drical projectile fitting telescopically over the same, and longitudinal ribs on said projectile between the ends thereof constituting supporting and steering surfaces therefor, said projectile being adapted to be discharged from said fluid pressure member by fluid pressure.

In testimony whereof, I affix my signature in the presence of two witnesses.

RICHARD LEHMANN.
